DANIEL W. SHANAHAN, OF LOWELL, MASSACHUSETTS, ASSIGNOR TO CHAMPION SHOE MACHINERY COMPANY, OF ST. LOUIS, MISSOURI, A CORPORATION OF MISSOURI.

MECHANISM FOR ATTACHING WELTS TO SHOES.

1,198,670.

Specification of Letters Patent. Patented Sept. 19, 1916.

Application filed September 19, 1914. Serial No. 862,525.

To all whom it may concern:

Be it known that I, DANIEL W. SHANAHAN, a citizen of the United States, and residing at Lowell, in the county of Middlesex 5 and State of Massachusetts, have invented a certain new and useful Improvement in Mechanism for Attaching Welts to Shoes, of which the following is a specification.

This invention relates to mechanism for 10 making shoes, and more particularly, to mechanism for attaching a welt to a McKay lasted shoe by a metallic seam passing through the insole.

Many attempts have been made to attach 15 a welt to the lasted upper of a McKay shoe by a seam passing through the welt, upper and insole, but without success, for the reason that it is exceedingly difficult, and, as a matter of fact, practically impossible to 20 properly position the welt on such an upper with the required accuracy. In the methods and mechanisms heretofore employed for that purpose, the horn has generally been utilized as a gage for gaging the position of 25 the seam with respect to the lasted shoe. It is, however, impossible to obtain, in this manner, a seam which will be positioned close, uniformly and accurately with respect to the contour of the shoe. If this seam is 30 not placed uniformly and close to the contour of the shoe, the shoe will not only present an undesirable appearance, but will not be water-tight and of sufficient strength to withstand wear.

35 It is possible to guide the shoe by the contour of the insole. In operating upon this shoe, however, the last is withdrawn, and the shoe is supported on a horn and is fed by an awl engaging the welt and the insole. 40 Now, the majority of insoles used in this type of shoe are flexible and light, and some of them are of low grade material and flimsy. It has been found, therefore, that, in withdrawing the last from such a shoe, there is 45 a liability of pulling the shoe out of shape. During the attachment of a welt, and during the feeding of the shoe over the horn, there is a further liability of pulling the shoe out of shape during this welt attaching operation.

50 In a shoe the welt must necessarily have a variable extension. Thus, in the shank the extension is small, being only sufficient for the outsole stitcher to properly support the 55 shoe when sewing the outsole to the welt.

At the ball, however, the extension is greater than at the shank, and this extension is greater on the outer than on the inner ball. It is, of course, obvious that a guide operating from the insole contour will not give this 60 extension unless a movable guide, adjustable by the operator during the operation of the machine, is used. Such adjustment is, however, objectionable, for the reason that it requires the attention of the operator, and, 65 therefore, decreases the output of the machine.

One of the objects of this invention, therefore, is to devise mechanism for attaching a 70 welt to a lasted upper by a seam of metallic fasteners passing through the insole, whereby the welt is laid on the upper so as to give an accurate extension and so as to accurately place the seam.

Another object is to devise mechanism for 75 attaching a welt to a lasted upper, whereby the shoe is guided and the welt and seam positioned by a predetermined contour or templet on the lasted upper.

Another object is to provide mechanism 80 whereby the welt is positioned and secured with a varying extension corresponding to the varying extension of the outsole.

Further objects will appear from the detail description taken in connection with the 85 accompanying drawing, in which:

Figure 1 is a detail front elevation of a fastener inserting machine embodying this invention; Fig. 2 is a detail side elevation; Fig. 3 is a bottom view of the guide; Fig. 4 is a section on the line 4—4, Fig. 3; Fig. 5 is a perspective view of the guide; Fig. 6 is a bottom view of a shoe upper with the templet in position and the welt attached; Fig. 7 is a section on the line 7—7, Fig. 6; Fig. 8 is a view similar to Fig. 7, but with the templet removed and the outsole attached; Fig. 9 is a section on the line 9—9, Fig. 7; Fig. 10 is a section on the line 10—10, Fig. 8; and, Fig. 11 is an enlarged detail of Fig. 10.

The machine may be any suitable fastener inserting machine, such as shown and described in U. S. Patent Number 1,091,298, March 24, 1914, but the particular embodiment shown is that shown and described in U. S. application Serial Number 830,050, filed April 6, 1914. In this machine, as shown in detail in Figs. 1 and 2, 10 designates a column or pillar supporting a machine head 11. This machine head has 110

mounted thereon a presser-foot 12, a vertically and laterally movable awl bar 13 carrying a piercing and feeding awl 14, a laterally movable throat 15, a driver 16, a fastener stock guide 17, a combined feeding and cutting member 18, and a coöperating cutter 19 on the throat. The usual horn 20, having a clenching anvil, is also provided. All these parts are of the construction shown and described in the application referred to, but may also be of the construction described in the patent referred to, and may use the same string of connected headed nails.

15 The presser-foot has secured thereto, by screws 25, the shank 26 of a welt guide which is positioned at an angle with respect to and extends underneath the presser-foot. This welt guide comprises an upper plate 29, cut away at 30 to permit entrance of the awl, and a lower plate 31 to form a recess or channel adapted to receive and guide the welting. The end of the welt guide projects a short distance below the presser-foot 25 so as to form a guide or gage face 32 adapted to coöperate with a contour on the outer insole face on the lasted upper, as herein-after described. The presser-foot may also have projecting therefrom and opposite the 30 driver a lug 33 whose forward edge is in alignment with the face 32 of the welt guide so as to coöperate with a contour on the insole. It is understood that either the face 32 or the lug 33 may be used for guiding the 35 shoe, or both may be used in conjunction.

The shoe comprises an insole 40 and an upper 41 lasted in accordance with the usual McKay method of lasting. The lasted upper has laid thereon a welt 43 secured there- 40 to by a seam of metallic fasteners 44 passing through and clenched on the insole. This fastener may be of substantially the construction shown and described in U. S. Patent Number 1,072,213, September 2, 1913.

45 An outsole 45 is attached to the welt by a line of stitches 46, and the space between the insole and outsole may be filled with the usual filling 47.

The operation of the mechanism in attaching the sole or bottom to this shoe is as follows: The upper is lasted in accordance with the usual McKay method of lasting. A contour or templet 42, of leather, leather board, or the like, is then positioned on 50 the lasted upper while on the last and temporarily secured by fasteners 48. This templet is died out or shaped to the contour of the outsole, but smaller, and is positioned on the upper in the same relation thereto as the 55 outsole in the completed shoe. The last is then withdrawn with this templet in position, and this templet will, therefore, reinforce and hold the shoe in shape while the last is being withdrawn. The shoe is now 60 placed on the horn with the edge of the

templet against the gaging face 32 of the welt guide, or against the gaging face of the lug 33, or both, and the machine started. As the machine starts, a fastener will be driven through the welt, upper and insole 70 and clenched on the insole by means of the clenching anvil on the horn. The end of the welt is thus attached to the lasted upper, and, during the operation of the machine, the awl will operate to successively 75 feed the welt and the shoe by the engagement of the awl with the welt, upper and insole. The shoe is guided, during the attachment of the welt, by the engagement of the guiding face 32 of the welt guide, or the 80 guiding face of the lug 33, with the edge of the templet, and since the welt is guided and positioned by this welt guide, the shoe will be accurately positioned with respect to the welt guide and the welt therein, so as to accurately position the welt with respect to the lasted upper. Since the outline of the templet corresponds to the outline of the outsole, it is, of course, obvious that the 85 welt will be positioned in such a relation 90 with respect to the shoe as to correspond in outline, as well as size, to the outsole. After the welt is attached, the templet 42 is removed, the bottom filled with a filling 47, and the outsole 45 laid and attached on an 95 outsole stitcher in the manner described in my application Ser. No. 862,524, filed of even date herewith. As heretofore described, the templet is placed in position while the 100 shoe is on the last, and before the last is withdrawn. This not only permits the templet to be accurately positioned with respect to the upper, since any gaging mechanism used for placing this templet in position may be gaged from the last, but it also 105 holds the shoe in shape while the last is withdrawn. It also stiffens the shoe while the welt is attached, and the operator can, therefore, hold the shoe in better shape. Since the guide follows the edge of the 110 templet, and since the outline of the templet corresponds to the outline of the outsole, it will be seen that the welt will have the same extension as the outsole, and, where the outsole has a varying extension, the welt can be 115 laid with a varying extension, corresponding to that of the outsole, by giving the templet the proper contour so as to give this extension. The welt will, therefore, be placed in such a manner as to make a correct and uniform edge. Since the welt is placed accurately with the outer edge corresponding to the outline of the outsole, this outsole can be died out to shape, so as to fit the outline 120 of the welt, while placed on the lasted upper. This not only permits the outsole to be laid with greater accuracy, but also permits the usual rough-rounding operation performed on welt shoes to be dispensed 125 with, thereby resulting not only in a saving 130

of time, but also in a saving of material. In practice, therefore, after the outsole is attached, it is only necessary to shape up the sole. The templet can be used a number of 5 times, and since it can be made of a cheap material, its expense will be very small.

It is obvious that various changes may be made in the details of construction without departing from the spirit of this invention, 10 and it is, therefore, to be understood that this invention is not to be limited to the specific construction described and shown.

Having thus described the invention, what is claimed is:

- 15 1. Mechanism for attaching welts to McKay-lasted shoes, comprising, a horn adapted to support a McKay-lasted upper, fastener inserting mechanism, welt guiding means, and means coöperating with a contour 20 separate from the welt and positioned on the outer insole face of the lasted upper adapted to position the shoe with respect to the welt.
2. Mechanism for attaching welts to shoes, comprising a horn adapted to support a lasted upper, fastener inserting mechanism, welt guiding means, a templet on the lasted

upper adapted to give a variable extension to the welt, and means coöperating with said templet adapted to guide the lasted upper to position the welt thereon.

3. Mechanism for attaching welts to shoes comprising a horn adapted to support a lasted upper, a presser foot, fastener inserting mechanism, welt guiding means, and 35 means projecting below said presser - foot and adapted to coöperate with a templet on the outer face of the lasted upper to guide the same and position the welt thereon.

3. Mechanism for attaching welts to shoes 40 comprising a horn adapted to support a lasted upper, fastener inserting mechanism, welt guiding means, a templet on the lasted upper shaped to the contour of the outsole, and means coöperating with said templet 45 adapted to guide the lasted upper to position the welt thereon.

In testimony whereof I affix my signature in the presence of these two witnesses.

DANIEL W. SHANAHAN.
